FIBER PICKER

Morris Mudrick, Los Angeles, Calif.

Application November 6, 1935, Serial No. 48,484

2 Claims. (Cl. 19—90)

This invention relates generally to fiber pickers and is specifically directed to devices adapted to soften and disentangle the matted threads of certain fibers for use as upholstery and mattress filling, by the violent impact of a series of rotating bars.

The filaments of the fibers usually employed in upholstery and the like, such as coconut, moss, cotton, sisal, kapok, and floss, contain natural oils which, due to the viscosity, are difficult to extract until thoroughly dry, which leaves the fiber a hard, matted mass of stiff threads, unsuited for use in upholstery or mattresses, without further treatment.

15 In the art prior to my invention, it has been found that the fiber may be softened and separated into light, yieldable threads by violent laceration and succession of the mass to break up the dried residue of the oil into a dust which is 20 then easily removed by a blower. However, the cost in both time and money incident to such prior art devices to successfully accomplish the results desired, as well as their complicity of structure, limits their utility, and restricts their 25 application to fiber which might otherwise have numerous additional uses.

It is a general object of my invention to provide a device in which dried, matted fiber may be disentangled, softened and loosened by violent 30 impact of a plurality of beater bars and teeth, having incorporated therewith means for the automatic removal of fiber, thus conditioned, to permit continuous feeding.

It is a particular object of the present invention to supplant or augment devices of the prior art, designed to lacerate or tear the fiber, by the provision of a rotor carrying a series of bars to beat and loosen dried adhesive substances from the fiber and by thus flexing the filaments to 40 restore elasticity and pliability thereto.

Another object is to provide a drum in which material may be disintegrated, loosened or flexed by the impact of a series of bars disposed on a shaft longitudinally extending below the central 45 axis of the drum to permit material to be thrown free of the bars above the shaft and prevent its accumulation on the floor of the drum.

Another object is the provision of a drum having a plurality of teeth disposed on its inner wall 50 against which matted or adhesive materials may be violently thrown by the impact of a series of beater bars, diametrically disposed on a rapidly rotated shaft, said teeth being inclined in the direction of rotation of said shaft to check the 55 movement of the material thus thrown and per-

mit its dropping back into the path of the bars without accumulating on the teeth.

Another important object of the present invention is the provision of a screened container into which dust and debris, shaken loose from the fiber by the impact of a series of rapidly rotating bars will settle for subsequent disposition.

Still other objects, such as durability, simplicity in both construction and operation, comparative economy of manufacture, wide scope of utility, 10 and facility of execution will be obvious to those of skill in this art.

In the drawings—

Fig. 1 is a plan view of the complete assemblage of my invention;

Fig. 2 is a side elevation of the device as shown in Fig. 1;

Fig. 3 is a section on line 3—3 of Fig. 1 depicting the working parts of my invention in detail;

Figs. 4 and 5 are sectional views on lines 4—4 and 5—5, respectively, of Fig. 3.

Referring to the drawings in detail, the numerals of which indicate similar parts throughout the several views, 10 designates a horizontally disposed drum, having end walls 11 and 12, supported on a base 13. Plates 14—14 are provided on opposite sides of drum 10 to reinforce its position relative to base 13. The upper half of drum 10 forms a door 15 which is hinged at 16 to facilitate access to the interior thereof for initially filling the drum with fiber, and cleaning, etc. Locking means for door 15 is indicated at 17, consisting of a series of staples protruding from the flanged lower half of drum 10 through holes in a flange 18 on the door 15, and secured by pins 19. A nut 20 having a handle 21 for manual manipulation is provided at the top of one end of the door which is adapted to screw into a flange 22 around the inner periphery of end wall 11 of drum 10. A chute 23 through end wall 12 of the drum facilitates the feeding of fiber into the drum as conditioned fiber is mechanically removed through the opposite end, as will be presently described. An exit opening 24 in end wall 11 of the drum is spaced near the bottom thereof through which fiber, after passing from chute 23 through the drum, is drawn into a circular fan housing 25 by a centrifugal fan about to be described, said housing being secured by any suitable means to the end of the 30 drum around opening 24.

Bearings 26 and 27 are mounted on base 13 at the outside of drum 10 below chute 23, and outside of housing 25, respectively, in which shaft 28, extending horizontally through drum 10 ap-

40 45 50 55

proximately one third the length of the diameter of the drum from the bottom thereof, is rotatably mounted. An electric motor, diagrammatically indicated at 29 (Figs. 1 and 2), is supported on 5 an extension of base 13 and adapted to rotate shaft 28 through a flanged connection 30 therewith. A collar 31 is splined to shaft 28 in housing 25 as designated at 32 on which are radially secured two oppositely disposed T irons 10 33-33. A pair of vanes 34-34 of a centrifugal fan are attached by rivets, bolts, or the like to T irons 33-33. Fiber, carried by the air flow, created by the fan, from chute 23 at one end of drum 10, through the drum, to the fan housing, 15 is discharged through a pipe 35 in housing 25. A series of beater bars 36, spaced apart at varying distances, extend diametrically through shaft 28 and are of a length sufficient to clear the bottom of drum 10 upon rotation of the shaft. Each 20 bar, beginning with the bar nearest end wall 12 of the drum is staggered 45° around the shaft in the direction of rotation thereof, with respect to the bar preceding it, thus as a bar passes through any particular radius of the circle in which the 25 ends of the bars are rotated, the shaft will make 135° of a complete rotation before carrying the next successive bar on the shaft through that radius which allows material thrown free of a bar against the wall of the drum to fall back into the 30 path of the next bar, as will be apparent in the description of the operation hereof to follow.

The outer end of each bar 36 is bevelled with the apex 37 of the bevel at the front of the bar thus facilitating rotation of the shaft by permitting 35 the bars to cut through hard material which may tend to wedge against the wall of the drum.

Matted fiber dropped through chute 23 is broken or partially separated by the first blows of the beater bars which facilitates its rotative pro- 40 gress through the drum as will be more in detail described. Due to the off-center position of the shaft and the length of the beater bars, none of the fiber is permitted to lay on the floor of the drum, but is constantly thrown by the impact of 45 the bars and the circulation of air outwardly and upwardly against the walls of the drum. A plurality of teeth 38, secured by rivets or the like, are disposed in a row, slightly below the longitudinal center of the drum on the wall thereof nearest 50 adjacent the upwardly rotating bars. Each of the teeth 38 are inclined in the direction of rotation of the shaft to prevent hooking and piling up of the filaments of the fiber thereon, as will be more fully described. A second row of 55 teeth 39, staggered with respect to the first row, are secured to door 15 of the drum just above row 38. Their degree of inclination from the diameter of the drum is slightly less than the teeth of row 38 as the velocity of the upwardly 60 moving blocks of fiber will be partially checked by their impact against the first row of teeth and their tendency to accumulate on teeth 39 will be accordingly reduced. On the inside of door 15 above shaft 28 two additional rows of teeth 40 65 and 41 are disposed in a manner similar to rows 38 and 39 and having the same relative degree of inclination. On the side of the drum opposite teeth 38 and 39 are located a third pair of relatively staggered rows of teeth, 42 and 43, the upper row 42 being inclined to a greater degree 70 than the lower row due to the movement of the beater bars at that side of the drum being downward and for the reason above referred to. The inclination of the teeth may be varied in particular modifications of my invention to facilitate 75

cleaning of the teeth by the momentum of the material itself and the circulation of air, as will be obvious to those of skill in this art.

Riveted to the underside of door 15 a guide 44 is provided consisting of an angle iron, having one end positioned over the upwardly moving bars 36 in a vertical plane between the two bars nearest end wall 11, and having its opposite end over the downwardly moving rotating bars in a plane between wall 11 and its adjacent bar. 10

A grille or screen 45 is provided in the floor of the drum proximate end wall 12 having a receptacle 46 therebelow riveted to the wall of the drum, to receive the bulk of the dust and debris shaken from the matted fiber in its preliminary treatment by the bars nearest chute 23. The flow of air from chute 23 at the top of the drum to opening 24 will promptly remove dust tending to settle in other parts of the drum. Accumulated dust may be removed from receptacle 20 46 through a door 47, hinged at 48, and provided with latches, diagrammatically illustrated at 49.

In the operation of the device dried blocks of matted fiber are slid into the drum through chute 23. The force of the initial impact of the rapidly 25 rotating bars 36 against the blocks of fiber break the blocks into several pieces before the fiber contacts the wall of the drum, thus permitting larger blocks of fiber to be inserted through chute 23 than would otherwise be possible. After passing 30 under the shaft 28, the partially broken material is thrown outwardly against the drum by centrifugal force where each pair of rows of teeth, particularly those provided at the top of the drum, check the swirling motion of the fiber and permit the same to fall into the path, and be 35 violently struck, by the bars 36, and the cycle is repeated until the fiber is removed through opening 24. It should be particularly noted that it is the alternate impact of the bars against the 40 fiber and the fiber against the teeth which causes its disintegration rather than laceration of the block by the teeth or other means.

Due to the concentrated weight of the matted fiber and the centrifugal force caused by the 45 rotating shaft and bars, the fiber is prevented from moving through the drum toward the opening 24 until it is thoroughly broken up, when its enlarged bulk and decreased weight comparatively 50 slows up its rotative movement and enables the suction created by the fan to draw the loosened fiber towards opening 24. When it reaches the bar at the opposite end of the shaft the now thoroughly disassociated filaments are thrown 55 against guide 44. The fiber is then directed by 55 the guide 44 toward end wall 11 where the forces of gravity and the suction of the fan combine to discharge the conditioned fiber through opening 24 and pipe 35 in the fan housing.

It will be seen that numerous changes may be 60 necessary to adequately condition different fibers which may vary in their tenacity and adhesive-ness of the threads, such, for instance, as the size of the drum, the speed of the shaft, or the size or relative power efficiency of the fan, all of 65 which will be obvious to those of skill in this art and within the scope of the appended claims.

It should be understood that I do not limit my invention to use with fibrous materials as it may be employed on numerous other materials, 70 adapted for disintegration by impact, with equal efficiency.

What I claim and desire to secure by Letters Patent is:

1. In a device of the character described, a 75

drum, a shaft, means to rotatably carry said shaft in said drum, a plurality of beater bars carried by said shaft, two rows of teeth on the inner wall of said drum, each tooth of the first 5 row located to the side of the other row from which the beater bars are moved being inclined in the direction of rotation of said shaft, and each tooth of said second row of teeth being inclined in the direction of rotation of said shaft 10 to a lesser degree with respect to the wall of said drum than the teeth of said first row.

2. In a device of the character described, a drum having its lower wall arcuate, a rotatable shaft in the lower portion of said drum parallel

to and in vertical alignment with the axis of the drum said shaft being disposed below the geometrical center of the arc formed by said wall, a plurality of beater bars carried by said shaft movable nearest said wall at its lowermost portion, a plurality of teeth of uniform cross-section secured on the inner surface of said drum inclined throughout their lengths in the direction of rotation of said shaft, said drum having an inlet opening and an exit opening at opposite ends 10 thereof, and means comprising a blower to draw material to be treated toward said exit opening.

MORRIS MUDRICK.
